UNITED STATES PATENT OFFICE.

HARLEY D. DRAKE, OF WASHINGTON, DISTRICT OF COLUMBIA.

DRIER.

1,403,016.

Specification of Letters Patent. Patented Jan. 10, 1922.

Application filed June 21, 1920. Serial No. 390,382.

To all whom it may concern:

Be it known that I, HARLEY D. DRAKE, a citizen of the United States, residing at Washington, in the District of Columbia, have invented certain new and useful Improvements in Driers, of which the following is a specification.

The present invention relates to driers and more particularly to such adapted to receive and confine clothes in the path of heat and is particularly well adapted for domestic use where steam, heated water, gaseous or liquid fuel may be used as a drying medium.

15 The principal objects of the invention are, to provide a drier which is compact and embodying racks for the clothes so arranged as to facilitate the placing and removal of the clothes and to dispose them in such a manner that the rising heat may effectively act upon the clothes in order to dry the same; and to provide a drier which is inexpensive to manufacture, efficient, and economical.

20 Other objects and advantages of the invention will appear in the following detailed description, taken in connection with the accompanying drawings, forming a part of the specification, and in which drawings:

25 Figure 1 is a front elevation of a drier embodying my invention.

Fig. 2 is a horizontal sectional view adjacent the bottom of the main body portion of the drier, showing the heater in plan.

Fig. 3 is an enlarged detail sectional view 30 on the line 3—3 of Figure 1.

Fig. 4 is a view similar to Figure 1, but showing the doors of the drier open and with the racks, for receiving the clothes, in elevation.

35 Fig. 5 is a horizontal sectional view through the upper portion of the drier main body portion, showing the racks in plan.

Fig. 6 is an enlarged detail view in elevation and section, showing a support for the 40 racks.

Fig. 7 is a top plan view of the main body portion of the drier.

Fig. 8 is a transverse vertical sectional view through the drier, with the racks and 45 their supports removed, being a section on substantially the line 8—8 of Figure 7.

Fig. 9 is an enlarged detail fragmentary section view on the line 9—9 of Figure 1.

Fig. 10 is an enlarged detail fragmentary sectional view on the line 10—10 of Fig- 55 ure 5.

Figure 11 is a detail sectional view, on an enlarged scale, on the line 11—11 of Fig- 60 ure 7.

Figure 12 is a view similar to Figure 10 on the line 12—12 of Figure 5.

In the drawings, where similar characters refer to similar parts throughout the several views, A designates the main body portion of the drier, which in the example shown is 65 relatively long and narrow, including a bottom B, top C, end walls D and back E, and is preferably supported on legs F with its bottom B in spaced relation to the floor level; G designates suitable closure means 70 for the main body portion A; H clothes supporting means in main body portion A; and J a heater, which in the example shown is adapted to conduct a heating medium, such as hot water or steam into the main body 75 portion A.

Referring first to the main body portion A it is preferred to form the same of sheet metal, rolled metal sections, material which is non-conducting to heat, such as asbestos, 80 and suitable fastening devices, so that the main body portion may be built up in a manner to remain in good repair, envelop clothes in a manner that the heat may effectively dry the same, and have good ap- 85pearance. With this end in view, in the example shown, there are provided four uprights 13, such as rolled metal of angular cross section and similar longitudinal and transverse members 14 and 15, respectively, 90 at the top and bottom of the main body portion. The top C, end walls D, and back E, may each be formed of inner and outer sheets 16 and 17, respectively, of metal, be- 95tween which is interposed a layer of non- conducting material 18, such as asbestos, these portions of the main body being se- cured to the rolled metal sections 13, 14 and 15, as by rivets 19, or in any suitable man- 100ner. The legs F may be a continuation of the sections 13, below the bottom B, and may be mounted upon a suitable base 20, and

if desired diagonal braces 21 may be secured to the base 20 and legs F, whereby the main body portion is rigidly supported with its bottom in spaced relation to the floor level.

- 5 It is preferred to provide in the bottom B and top C openings 22 and 23, respectively, these being preferably formed by cutting substantially H-shaped incisions in the top and bottom and bending portions of 10 the material to provide flanges 24 and 25, for the openings 22 and 23, respectively, these flanges extending outwardly and being movable so as to provide for adjustment as to the size of the openings. The openings 15 22 permit ingress of air into the drier, while the openings 23 provide an egress for the air, and by moving the flanges of these openings toward or from each other a quantity of air admitted into the main body portion 20 or finding exit therefrom, may be regulated. The flanges 24 of openings 22 also, being disposed downwardly extending with respect to the openings, shed any water which may drip from the clothes disposed in the 25 drier. If desired a pan, not shown in the drawings, may be disposed beneath the drier to catch any of the drippings.

A front opening 26 in the main body portion, through which access to the interior 30 may be had, may be closed in any suitable manner, and in the example shown comprises the doors G, hinged as at 27 to the uprights 13. These doors may be of metal and in the example shown contain dead air 35 spaces 28. The doors may be held in closed position, in any suitable manner, such as by bolts 29 carried by the doors adapted to engage keepers 30 secured to the main body portion, these bolts being actuated by a lever 40 31.

Referring now to the clothes supporting means H it comprises a plurality of racks 32; means 33 pivotally supporting the racks at one end portion adjacent one end of the 45 main body portion A; and a suitable rest 34 for supporting the racks adjacent the other end portion of the main body. It is preferred to form the racks of a top rail 35 and a plurality of relatively shorter rails 36; and stiles 37 and 38. The stiles 37 may be 50 adapted, as hereinafter noted, to serve as the pivotal portion of the rack, and it is preferred to dispose the stiles 38 inwardly of the end portion of top rails 35, so that the latter have extensions 40 for a purpose to be 55 subsequently set forth. If desired suitable braces 39 may be disposed between the rails and stiles 37.

If made of wood, the stiles 37 may have 60 disposed at their end portions metallic angles 41 secured thereto in any suitable manner and metallic spindles 42 adapted to engage the means 33 hereinbefore referred to. This means for pivotally supporting the 65 racks may comprise bars 43 and 44, the bar

43 being adjacent the bottom of the main body portion, and the bar 44 adjacent the top thereof. It is preferred to connect these bars with the main body portion in a manner that they may be readily removed if it is 70 desired to repair any of the rack, or replace them by racks of different configuration. With this in view the bars may be supported by brackets 45 and detachably secured thereto as by bolts 46 provided with nuts 47, 75 shown more in detail in Figure 12, of the drawings. The bars are provided with perforations 48, forming bearings for the spindles 42. The rest 34 may consist of an angular piece of metal secured to one end portion of the main body and may be provided with lugs 49, struck therefrom and bent upwardly. This rest is adapted to receive the extending portions 40 of the top rails 35 and the lugs 49 to engage these extended portions laterally, so as to hold the racks in spaced relation. It is preferred to make the perforations 48 in the bars 43 and 44 relatively larger than the spindles 42, so that the racks may be slightly rocked in a vertical 80 plane in order to swing the racks over these lugs 49.

In order that the racks 32 may be swung outwardly of the main body portion A, through the opening 26, in close relation to 95 one another, it is preferred to dispose the bars 43 and 44 so that the vertical axes of rotation of the racks are near one end of the main body portion and in a vertical plane diagonally cross-wise of the vertical plane 100 coincident with the major axis of the main body portion, as clearly shown in Figures 4 and 5 of the drawings. With reference more particularly to Figure 5, the dotted position of the racks show their relative 105 position when swung outwardly, that is, in close relation, while the full lines indicate the position of these racks within the main body portion, in spaced relation. The racks are thus detachably carried by the main body 110 portion and pivotally supported in juxtaposed relation at their stiles in a manner that the stile of the rack nearest the opening 26 is nearest one end of the main body portion and each succeeding rack is disposed 115 with its pivot further away from the said end of the main body portion. Ample room is thus provided between the doors G for a person to stand when placing clothes on the racks when they extend outwardly of 120 the opening 26, and when swung inwardly, will be in substantial spaced relation, so that the heat from the heater J may rise between and under the clothes disposed on the rails of the rack. When disposing clothes on the 125 rack, the smaller pieces are first placed on the lowermost rail 36 and the larger pieces on the super-jacent rails.

In the example shown I have disclosed the heater J as comprising a plurality of longi- 130

tudinally extending pipes or coils, resting upon supports 51 beneath the racks 32, but this is merely by way of example since any desired heater may be provided. In the example shown, these pipes are intended to conduct steam, or hot water and where the latter is used, it is preferred to have the ingress 52 of the pipe lower than the egress 53. The supports 51 are therefore provided with inclined upper faces, which incline upwardly from the front of the main body portion A.

When bringing the drier into use, the clothes are disposed on the racks as hereinbefore described with the smaller pieces lowermost so that there is a tendency to spread the larger pieces of material disposed over the rails, at their lower portions so that the heat may rise under the clothes. If the heater is disposed in a position where there is considerable draft, the flanges 24 and 25 may be moved toward each other thus reducing the size of the openings 22 and 23.

Changes in details may be made without departing from the spirit or scope of my invention; but

I claim:

1. A clothes drier comprising in combination, a main body portion adapted to envelop the clothes and including a top and bottom each provided with openings having outwardly extending movable flanges to permit ingress of air from the bottom into the main body portion and egress of air therefrom at the top, said flanges being adjustable to regulate the draft of air through the drier and the flanges of said bottom inclining downwardly therefrom to shed water from the interior of the main body portion, a clothes supporting means in said main body portion, and a heater below said clothes supporting means.

2. A clothes drier comprising in combination, a main body portion adapted to envelop the clothes and including a bottom provided with openings having downwardly extending movable flanges to permit ingress of air to the interior of the main body portion, said flanges inclining downwardly from the bottom to shed water from the interior of the main body portion, a clothes supporting means in said main body portion, and a heater below said clothes supporting means.

3. A clothes drier comprising in combination, a main body portion adapted to envelop the clothes and including a metallic top and bottom each provided with openings formed by providing substantially H-shaped incisions therein and bending portions therefrom to provide outwardly directed flanges to permit ingress of air from the bottom into the main body portion and egress of air therefrom at the top, said flanges being adjustable to regulate the

draft of air through the drier and the flanges of said bottom inclining downwardly therefrom to shed water from the interior of the main body portion, a clothes supporting means in said main body portion, and a heater below said clothes supporting means.

4. A clothes drier comprising in combination, a main body portion adapted to envelop the clothes and including a metallic bottom provided with openings formed by providing substantially H-shaped incisions therein and bending portions therefrom to provide downwardly extending flanges to permit ingress of air to the interior of the main body portion, said flanges inclining downwardly from the bottom to shed water from the interior of the main body portion, a clothes supporting means in said main body portion, and a heater below said clothes supporting means.

5. A clothes drier comprising in combination, a relatively long narrow main body portion adapted to envelop the clothes and provided with an opening through which access to the interior of the main body portion may be had, a plurality of racks swingable into and from said main body portion and each rack including a horizontal top rail, relatively shorter parallel rails in spaced relation therebeneath, and end stiles connecting said rails at end portions with a portion of the said top rail extending beyond the stile at one end of the rack, means pivotally mounting said racks in said main body portion adjacent one end thereof, a rest at the other end of said main body portion upon which the extended end portions of said top rails of said racks may engage said rest provided with spaced apart stops to engage the said extended portions laterally, closure means for the main body portion and a heater below said racks.

6. A clothes drier comprising in combination, a relatively long narrow main body portion adapted to envelop the clothes and provided with an opening through which access to the interior of the main body portion may be had, a plurality of racks swingable into and from said main body portion and each rack including a horizontal top rail, relatively shorter parallel rails in spaced relation therebeneath, and end stiles connecting said rails at end portions with a portion of the said top rail extending beyond the stile at one end of the rack, means pivotally mounting said racks in said main body portion adjacent one end thereof, a rest at the other end of said main body portion upon which the extended end portions of the top rails of said racks may rest, closure means for the opening of said main body portion, and a heater below said racks.

7. In a clothes drier, the combination, of a relatively long narrow main body portion adapted to envelop the clothes and provided

with an opening through which access to the interior of the main body portion may be had, a plurality of racks, each including a plurality of spaced apart horizontal rails and stiles at opposite end portions of said rails, one of said rails being relatively longer than the others and extending beyond one of said stiles, means pivotally mounting

said racks in said main body portion adjacent one end thereof, a rest at the other end 10 of said main body portion upon which the extended end portions of the relatively longer rails of said rack may engage, closure means for the opening of said main body portion, and a heater below said racks. 15

HARLEY D. DRAKE.
